US00D597430S

(12) **United States Design Patent**
Sloan et al.

(10) **Patent No.:** US D597,430 S
(45) **Date of Patent:** ** Aug. 4, 2009

(54) **OCCUPANCY SENSOR**

(75) Inventors: **Greg Edward Sloan**, Allentown, PA (US); **Andrew Peter Schmalz**, Macungie, PA (US)

(73) Assignee: **Lutron Electronics Co., Inc.**, Coopersburg, PA (US)

(**) Term: **14 Years**

(21) Appl. No.: **29/322,082**

(22) Filed: **Jul. 29, 2008**

(51) **LOC (9) Cl.** **10-05**

(52) **U.S. Cl.** **D10/104**; D10/106

(58) **Field of Classification Search** D10/104, D10/106, 70; 340/584, 567, 541, 501; D13/152, D13/169, 171; 709/217; 174/535; 248/218.4; 455/420; 361/674, 748; 362/431, 432; D14/155; 438/667; 250/353; 323/282; 315/246

CLAIM

The design for an occupancy sensor, as shown and described.

DESCRIPTION

FIG. 1 is a perspective view of the top of the occupancy sensor, seen from one side of the occupancy sensor;

FIG. 2 is a top plan view of the occupancy sensor; and,

FIG. 3 is a side elevation view of the occupancy sensor.
